RENÉ EMILE TROTTIER, OF PARIS, FRANCE.

SYSTEM OF RIFFLING OSCILLATING TABLES FOR THE TREATMENT OF ORES.

1,356,179.

Specification of Letters Patent. Patented Oct. 19, 1920.

Application filed July 29, 1919. Serial No. 313,970.

To all whom it may concern:

Be it known that I, RENÉ EMILE TROTTIER, citizen of the Republic of France, and resident of 39 Rue de la Boëtie, Paris, in the said Republic, engineer, have invented a new and useful System of Riffling Oscillating Tables for the Treatment of Ores, of which the following is a specification.

Hitherto, oscillating tables employed for 10 the concentration and separation of ores, particularly such tables as are used in the Wilfley system, have generally been provided on their upper surface with ridges or riffles, of appropriate section and length, for 15 retaining and guiding the detained particles toward one end of the table, on which they are spread out in layers of different specific gravities. These layers, progressing along the table under the influence of the oscillating 20 movements, are deflected along the two sides of the table, and the component substances can be separately collected. However, as the size and the direction of the 25 layers of different densities vary with the feed and the nature of the ores being treated, tables of this kind need constant supervision while in work in consequence of the necessity of varying continually the devices adopted for directing the separated substances 30 toward the receptacles destined to receive them.

The invention consists in a special system of riffling for tables of this kind, which has for its object to obviate the above mentioned 35 inconvenience. The system consists essentially in providing the table area with riffles of convenient profile for forming, in the longitudinal direction, regular undulations, very extensive, which for preference suitably 40 overlap one another in the direction of the advance of the ores, in a manner to permit the spreading out thereof and to facilitate their separation.

The whole riffling constitutes across the 45 table a surface having short and regular undulations whose height varies gradually from one section of the table to the following section. In this way the ore which, on the first part of the table, is confined between two adjacent riffles passes out therefrom as soon as it arrives at the mean part 50 thereof, and is spread out according to its specific gravity on a flat portion of the table to pass subsequently between extensions of the two next adjacent riffles which act as collectors and lead to the outlet. The ores thus

separated by the conducting riffles can be separately collected, without risk of mixing or disturbance of the classification.

The accompanying drawing shows the detail of an oscillating table provided with a system of riffling the object of the invention. Figure 1 is a plan view of the table, Figs. 2 and 3 are two cross sections made respectively along the lines A B and C D of Fig. 1. Figs. 4 and 5 are two longitudinal sections made respectively along the lines E F and G H of Fig. 1. Fig. 6 is a diagram showing the manner of arranging the riffles.

As is seen from the drawing, the table 70 consists of a shelf *a* (Figs. 2, 3, 4 and 5) which supports at one of its upper corners, the ore distributing device *b* that is adjustable in position.

Above the upper longitudinal margin of 75 this shelf is situated the channel *c* for the supply of water which falls onto the upper margin *c'* of the table. The shelf *a* carries longitudinal riffles *d*, of variable profile, disposed side by side and so that to the high 80 part of one riffle is juxtaposed the low part of the adjacent riffle so as to form between all the riffles a series of channels of variable section along which the ore advances. The transverse section of these riffles is rectangular, while their longitudinal section is of a sinuous or up and down form with very extensive undulations. On Fig. 1 the low part *d'* of the riffles is denoted by shading 85 while their higher parts *d*² are left clear. The longitudinal undulations, however, overlap one another, at every two riffles, according to a law of regular advancement, so that all the lower parts of one series of 90 riffles and the higher parts of the other 95 series are disposed along the same oblique line *X X'* starting from the upper feed corner of the table which thus presents, at a distance varying according to the amplitude of the undulations, a mean flat part 100 having its axis along a line *Y Y'* parallel to the line *X X'*. This arrangement is depicted in the diagram in Fig. 6, where successive riffles are represented in section and turned down into the plane of the table in 105 order to show clearly their profile. The pitch of the undulations is equal in the example illustrated, to the length of the table surface and the maxima and minima of the respective undulations may be repeated 110 along the line *X² X²* (Fig. 6) which is parallel to the line *X X'* and drawn across the

upper corner of the table opposite to the feeding corner. The length of the table and the pitch of the undulations of the riffles are variable and depend on the nature of the ore 5 to be treated, the inclination of the line Y Y' (and consequently of the line X X' which is parallel with it) being substantially that of the mean tangent to the parabolic curve of advancement of the ore on the table 10 under the effect arising from the movement of this latter. The table, for example, instead of supporting only the length of a single undulation spire per riffle, can evidently support riffles of two or more consecutive spires so that the operation of classifying can be effected two or more times along the length of the table.

Instead of being independent, the riffles can very well be integral with one another 20 the whole being molded out of the same appropriate material, to the desired profile.

The classifying operation with an oscillating table provided with the improved system of riffles is as follows:

25 The core fed in by the distributor b, suitably arranged, falls on to the table in the neighborhood of the feeding corner a', whence the oscillating movements immediately make it progress in the direction of 30 the opposite end. Water being regularly admitted by the conduit along the side a' a² of the table, flows toward the opposite side a³, a⁴, with a speed dependent on the slope of the table in the transverse direction, that 35 is to say, in the direction a' a⁴, and consequently tends to carry the ore along that slope.

In consequence of the vertical classification according to specific gravity which occurs 40 in the different longitudinal channels formed between the riffles, the heavier particles of ore pass rapidly to the bottom of these channels while the lighter particles on the contrary overflowing and passing 45 over successively all the riffles flow along the lower margin a³ a⁴ of the table. The heavy particles, retained according to the specific gravity between successive riffles tend to advance and debouch on to the neutral or 50 flat zone (along Y Y') of the table, where they immediately spread out into layers whose size varies with the feed and the nature of the ore treated.

The water from the feed conduit tends on 55 the contrary, while following the cross slope of the table, to follow the longitudinal channels along their slopes, in the direction opposite to the advancement of the ore in the first zone of undulations that is to say, to the right of the line X X', while it tends on 60 the contrary to advance in the direction of this progression in the second zone of the undulations, that is to say, to the left of the line X X', since the slope of the chan-

nels changes in direction at that line. The 65 result is, that in the first zone the water acting on the lighter particles draws them to the right of the table, while in the second zone its action facilitates the progress of the denser particles toward the neutral or 70 mean part of the table.

It will be seen that this somewhat divergent action of the water on the particles to be treated, combined with the drawing action on the particles due to the movement of 75 the table, will facilitate the spreading out of the bodies and consequently their separation, so that on their arrival in the neutral zone of the table, the particles will separate and classify themselves, so much the better, 80 according to their specific gravities in distinct layers.

In consequence of their progressive movements the different layers meet immediately, beyond the line Y Y', a second zone of 85 riffles, between which they are channeled and progress to flow, perfectly separate, along the side a² a³ of the table without being able to become mingled afresh, as will happen if the outlet end of the table does not present 90 any device for collecting them and maintaining them separate by directing them toward the outlet.

It goes without saying that the described system of riffling may be applied to oscillating tables of all kinds, no matter what may be the mode by which they are controlled and moved.

Having thus described the nature of the said invention and the best means I know of 100 carrying the same into practical effect, I claim:—

A system of riffling for oscillating tables for treatment of ores, which comprises an inclined shelf forming a table, an ore feeding device at one of the upper corners of the table, a water supply conduit along the upper margin of the table, longitudinal riffles arranged side by side on the table and having longitudinal undulations formed thereon and overlapping in such a way that the high part of one riffle is aside of the low part of the adjacent riffle so as to form longitudinal channels adapted to retain and guide the ore, a neutral zone constituted by 110 adjacent parts of the same height of all the riffles, for the purpose of assisting the spreading out and the separation of the ores, and extensions of the said riffles which form collectors to conduct the separated ores, 115 without risk of being re-mixed, to the outlet.

In testimony that I claim the foregoing as my invention, I have signed my name this twenty-sixth day of June, 1919.

RENÉ EMILE TROTTIER.
